UNITED STATES PATENT OFFICE.

THOMAS A. DICKS, OF PITTSBURGH, PENNSYLVANIA, ASSIGNOR TO STANDARD STEEL PROPELLER COMPANY, OF PITTSBURGH, PENNSYLVANIA.

PROPELLER.

1,383,791.

Specification of Letters Patent. Patented July 5, 1921.

Application filed January 8, 1920. Serial No. 350,207.

To all whom it may concern:

Be it known that I, THOMAS A. DICKS, a subject of Great Britain, and residing at Pittsburgh, in the county of Allegheny and 5 State of Pennsylvania, have invented certain new and useful Improvements in Propellers; and I do hereby declare the following to be a full, clear, and exact description of the invention, such as will enable 10 others skilled in the art to which it appertains to make and use the same.

This invention relates to improvements in propellers and more particularly to that type in which the blades are adjustable, 15 objects of the invention being to provide simple and efficient means whereby a propeller having a metallic hub and metallic blades may be angularly adjusted so as to change the pitch of the blades as desired 20 and positively secure the blades in the positions to which they may be adjusted and to so construct the propeller and its adjusting mechanism that the degree of pitch of the blades may be decreased when the machine 25 is starting; increased when the machine is flying, and so that the blades may be adjusted to "no pitch" or zero and so that the pitch may be reversed to facilitate the slowing down of an aeroplane or dirigible after landing, in order to land within 30 a small area.

With these and other objects in view, the invention consists in certain novel features of construction and combinations of parts as 35 hereinafter set forth and pointed out in the claims.

In the accompanying drawings; Figure 1 is a view partly in elevation and partly in section and broken away, illustrating an 40 embodiment of my invention; Fig. 2 is a view in section on the line 2-2 of Fig. 1; Fig. 3 is an end view; Fig. 4 is an elevation of a propeller and adjusting mechanism for the blades thereof; Fig. 5 is a longitudinal 45 section of the metallic tube before being formed into a propeller blade; Fig. 8 is an end view of the same, and Figs. 6, 7 and 9 are views illustrating one of the metallic blades.

50 1 represents a portion of the engine body or crank case of an aeroplane, and 2 the engine shaft to which the propeller is attached. The hub 3 of the propeller (a portion 3a of which may have an angular ex-

terior) is secured to the engine shaft in any 55 suitable manner and it may be composed of a hollow steel forging having tubular arms 4 which enter the inner cylindrical ends of tubular blades 5 and on which arms, said blades are mounted in a manner to permit 60 their angular adjustment. Each blade may be made from a steel tube 6 (Figs. 5 and 8) and formed by any suitable method to the shape shown in Figs. 6, 7 and 9.

A sleeve 7 is threaded on each hub arm 65 and extends approximately to the outer end of the latter. The outer end portion of this sleeve is recessed to receive bearing rings 8 and a ring 9 is threaded on the outer end of the sleeve to retain said bearing 70 rings in place. A bearing ring 10 is located within the tubular blade and between the ring 10 and the rings 8, anti-friction balls 11 are located. A sleeve 12 is threaded into the tubular blade, rearwardly of the sleeve 75 7 and between these sleeves, bearing rings 13 and 14 are disposed and spaced apart to receive anti-friction devices, (such as cone rollers 15) between them, and a ring 16 may be disposed in the blade so as to surround 80 the cones 15. Rearwardly of the sleeve 12 and engaged by the rear end thereof, a bearing ring 17 is located within the blade and a bearing ring 18 is located in an annular recess in the hub arm, anti-friction balls 19 being 85 disposed between these bearing rings. A sleeve 20 on the hub arm is disposed between the bearing rings 13 and 19 to prevent displacement thereof. A ring 21 is threaded into the inner end of the tubular blade and 90 retains the bearing ring 17 in place. A screw indicated at 22 may be passed through the wall of the tubular blade and made to enter the sleeve 7 to hold the parts in position while assembling the bearing devices. 95

It will be seen that the tubular blades are mounted on the hub arms in such manner as to insure free turning thereof for adjusting purposes and that the thrust of the blades due to centrifugal force is effectively 100 cared for.

Pins 23 are made rigid with the inner ends of the blades 5. In the present instance I have shown these pins as projecting from bands 24 secured to the blades. 105 With these pins, adjusting mechanism cooperates to effect adjustment of the blades and this mechanism will now be explained.

A sleeve 25 is slidably mounted on the hub 3 and is provided with arms 26 movable against two flat sides of the angular portion 3^a of said hub,—said arms being guided in by plates 27 rigidly secured to the hub portion 3^a and overlying the arms 26. Angular lugs 28 are made rigid with the arms 27 (preferably integral therewith) and the outwardly projecting members of said lugs are made with elongated slots 29 to receive the pins 23 at the inner ends of the blades. The sleeve 25 is made with two annular flanges 30, 30, forming an annular groove between them which receives bearing rings 31. A ring 32 surrounds the flanged portion of the sleeve 25 and receives a bearing ring 33 and between the latter and the bearing rings 31, antifriction balls 34 are located. Means are provided (as hereinafter explained) for shifting the ring 32 to slide the sleeve 25, and in order to prevent possibility of cramping of the bearing devices between these members, the groove in the ring 32 is such as to make the internal diameter appreciably greater than the external diameter of the bearing ring 33, as indicated at 34, Fig. 1.

The shifting ring is provided with arms 35 having holes through which screws 36 are threaded. These screws are mounted to turn in bearings 37 on a bracket 38, the latter being secured to the engine body or crank case 1. Pinions 39 are secured to the rear ends of the screws 36 and mesh with a ring gear 40 mounted on the bracket 38,—ball-bearing devices 41 being disposed between said ring gear and an annular flange 42 on the bracket,—said flange serving, in effect, as a hub for said ring gear. A shaft 43 is mounted in the bracket 38 and has secured thereto, a gear 44 disposed in the bracket 38 and meshing with the ring gear 40. The shaft 43 may be extended to a position within convenient reach of a navigator and may be provided with any suitable hand device to facilitate its manipulation.

It will be apparent that if the shaft 43 be turned, motion will be transmitted, through the gearing and the screws 36 to the shifting ring 32 to slide the sleeve 25 and that the sliding of this sleeve will transmit motion, through the arms 26, lugs 28 and pins 23 to the blades to turn the latter about their axes and thus adjust the angularity of the blades.

With the use of the mechanism hereinbefore described, the angularity of the blades may be adjusted at any desired pitch as may be found desirable, or adjusted so that they will have no pitch or their pitch reversed.

To whatever adjustment the blades may be set, they will be effectually locked in such adjustment by the action of the screws 36.

Various changes might be made in the details of construction of my invention, with-

out departing from the spirit thereof or limiting its scope, and hence I do not wish to restrict myself to the precise details herein set forth.

Having fully described my invention what I claim as new and desire to secure by Letters Patent, is:—

1. A propeller comprising a hub having arms, blades having tubular portions receiving said arms and mounted to turn thereon, adjusting means for said blades mounted on the outside of the hub and engaging exterior parts of the blades, and means for operating said adjusting means.

2. The combination of a propeller hub, hollow blades, arms on the hub entering said blades and providing revoluble mountings for the latter, manually controlled adjusting means mounted on said hub and connected with said blades for effecting angular adjustment thereof, and means for operating said adjusting means.

3. The combination with a propeller hub and angularly adjustable blades carried thereby, of a sleeve mounted to slide on said hub and having approximately diametrically opposite arms, slotted lugs projecting from said arms, pins carried by the blades and entering the slots of said lugs, and means for moving said sleeve longitudinally of the hub.

4. The combination with a propeller hub having arms, and propeller blades having revoluble mountings on said arms, of a sleeve mounted to slide on said hub, arms on said sleeve, slotted lugs on said arms, pins on said blades entering the slots of said lugs, and means for sliding said sleeve to effect angular adjustment of the blades.

5. The combination with a propeller hub and angularly adjustable blades connected therewith, of arms mounted to slide on said hub, pin-and-slot connections between said arms and the blades, and means for moving said arms longitudinally on the hub to effect angular adjustment of the blades.

6. The combination with a propeller hub and angularly adjustable blades connected therewith, of a slidably-mounted sleeve provided with arms disposed alongside the hub, guide plates secured to the hub and overlying said arms, pin-and-slot connections between said arms and the propeller blades, and means for moving said sleeve and arms to effect angular adjustment of the blades.

7. The combination with a propeller hub and angularly adjustable blades connected therewith, of a slidably-mounted member provided with arms disposed alongside the hub, connections between said arms and the propeller blades whereby the latter may be angularly adjusted when said arms are moved relatively to the hub, and means including a screw for sliding said arms to effect angular adjustment of the blades and

for locking said arms against movement to hold the blades in the positions to which they may be adjusted.

8. The combination with a propeller hub 5 and angularly adjustable blades connected therewith, of a sleeve slidingly mounted on the hub, arms carried by said sleeve and disposed alongside the hub, means between said arms and the blades to effect angular adjustment 10 of the latter when the arms are moved, a shifting ring within which said sleeve is rotatable, screws having threaded connections with said shifting ring, pinions carried by said screws, a gear meshing with 15 said pinions, a driving gear meshing with said first-mentioned gear, and means for turning said driving gear.
9. The combination with a propeller hub and angularly adjustable blades connected 20 therewith, of a sleeve mounted to slide on the hub, arms carried by said sleeve, alongside the hub, pin-and-slot connections between said arms and the blades for effecting angular adjustment of the latter when 25 said sleeve and arms are moved, a supporting bracket, a shifting ring encircling said sleeve, anti-friction devices between said shifting ring and said sleeve, screws having

threaded connections with the shifting ring and mounted on said bracket, pinions secured to said screws, a gear ring mounted on said bracket and meshing with said pinions, bearing devices for said gear ring, a driving gear mounted on said bracket and meshing with said gear ring, and an operating shaft for said driving gear.

10. In a propeller, the combination with blades having tubular inner end portions, and a hub provided with arms entering the tubular inner end portions of the blades, 40 anti-friction bearing devices within said blades and around the hub arms and acting to withstand end thrust of the blades and to insure free turning of said blades about their axes, sliding means mounted on the 45 hub and connected with the blades to effect angular adjustment of the latter, and manually controlled means for operating said sliding means.

In testimony whereof, I have signed this 50 specification in the presence of two subscribing witnesses.

THOMAS A. DICKS.
